UNITED STATES PATENT OFFICE.

FRANK CANFIELD, OF DENVER, COLORADO, ASSIGNOR, BY DIRECT AND MESNE ASSIGNMENTS, TO JOHN ALEXANDER MACDONALD AND HOWARD C. BONSALL, OF DENVER, COLORADO.

CLOSURE-FASTENING DEVICE.

SPECIFICATION forming part of Letters Patent No. 783,994, dated February 28, 1905.

Application filed May 31, 1904. Serial No. 210,593.

To all whom it may concern:

Be it known that I, FRANK CANFIELD, a citizen of the United States, residing in the city and county of Denver and State of Colorado, 5 have invented certain new and useful Improvements in Closure-Fastening Devices; and I do declare the following to be a full, clear, and exact description of the invention, such as will enable others skilled in the art to which it applies to make and use the same, reference being had to the accompanying drawings, and to the letters of reference marked thereon, which form a part of this specification.

My invention relates to improvements in a 15 fastening device for the closures of receptacles, as jars or other receptacles adapted to contain substances which it is desired to seal from contact with the atmosphere. It is also necessary that these receptacles should be both air and 20 liquid tight.

My object is to provide a device of this class which shall be simple in construction, economical in cost, reliable, durable, and efficient in use; and to these ends the invention consists 25 of the features hereinafter described and claimed, all of which will be fully understood by reference to the accompanying drawings, in which is illustrated an embodiment thereof.

In the drawings, Figure 1 is a side elevation 30 of a jar the cap of which is held in place by my improved fastening device, the latter being in the locked position. Fig. 2 is a section of the jar, the cam-lever being shown in longitudinal section and in the unlocked position. 35 Fig. 3 is a top or plan view of the device shown in Fig. 1 and with the parts in the same position. Fig. 4 is a top view of the device, showing the cam-lever in the unlocked position. Fig. 5 is a section taken on the line 40 5, 5, Fig. 1, viewed in the direction of the arrow.

The same reference characters indicate the same parts in all the views.

Let A designate a jar or other suitable receptacle, to which is applied a cap A', resting on a packing-washer A². As shown in the drawings, the cap A' is provided with a specially-prepared wearing-plate A³, the said plate being provided with a depending thread-

ed shank A⁴, passing through an opening in the top of the cap and protruding into the hollow 50 of the cap. This protruding extremity is threaded, and to it is applied a nut A⁵ for holding the plate in place. Surrounding the threaded shank and engaging the inner surface of the cap is a rubber washer A⁶, and 55 between this rubber washer and the nut is a metal washer A⁷.

In the opposite sides of the wall of the receptacle A are formed recesses A⁸, into which are bent the extremities B' of a fastening-bail 60 B, formed from a single piece of wire and extending above the cap. In the center of this wire bail is formed an eye B², through which is passed a pin B³, upon which a cam-lever C is fulcrumed. This lever is cut away, as 65 shown at C', to make room for the bail when the lever is thrown to the unlocked position, as shown in Fig. 2. The arm of the cam-lever is provided with a central slot C². Projecting from the arm on opposite sides of this 70 slot are two curved lips C³. The central portions of these lips approach each other, and they bend outwardly in both directions. They are sufficiently close together that when the cam-lever is forced downwardly upon the bail 75 the latter spreads the lips apart until the bail is passed between them, after which the lips close below the bail and lock the lever securely in place. The lips are practically rigid; but the split or slot C² of the lever allows the two parts of the lever sufficient 80 spring or yielding capacity to permit the lips to open and close in the performance of their function. As shown in the drawings, the slot C² extends from the free extremity of the lever inwardly toward its cam extremity a suitable 85 distance to permit the performance of the aforesaid function.

From the foregoing description the use and operation of my improved device will be readily understood. Assuming that the parts are assembled and that the cam-lever is in the unlocked position, or that shown in Figs. 2 and 4 of the drawings, it is only necessary to throw the cam-lever downwardly to the position shown in Figs. 1 and 3, when the cam of

the lever acts on the wearing-plate to force the cap down tightly-forming an air-tight and water-proof joint between the cam and the body of the jar or receptacle. At the same time the 5 lips C^o come in contact with the bail, and spread apart by virtue of the split in the arm of the lever sufficiently to permit the bail to enter, after which the lips close beneath the bail and hold the lever in the locked position 10 and perfectly secure against accidental displacement.

Having thus described my invention, what I claim is—

1. In a device of the class described, the 15 combination with a receptacle and a cap therefor, of a bail pivotally connected with the wall of the receptacle, a cam-lever fulcrumed on the bail and whose cam portion is adapted to engage the top of the cap to hold the latter securely in place when the lever is thrown to the locking position, the lever having a pair of yielding lips adapted to pass on opposite sides of the bail and lock the lever in the closed position, substantially as described.
2. The combination with a receptacle and a cap therefor, of a bail connected with the receptacle and adapted to pass upwardly over the cap, a cam-lever fulcrumed on the bail and having its arm slotted and provided with 30 lips projecting from the arm on opposite sides

of the slot, the said lips being adapted to straddle the bail and lock the lever in the closed position, substantially as described.

3. The combination with a suitable jar or other receptacle, and a cap therefor, of a bail 35 connected with the body of the receptacle and adapted to extend upwardly over the cap, a cam-lever fulcrumed on the bail, the arm of the lever being split from its free extremity inwardly a suitable distance, and curved lips 40 projecting from the lever on opposite sides of the slot, the two lips being adapted to engage the bail and hold the lever in the locked position as set forth.

4. The combination with a receptacle, of a 45 cap, a wearing-plate applied to the top of the cap and having a threaded shank extending therethrough and protruding from the interior thereof, fastening means applied to the shank on the inside to hold the wearing-plate in position, a bail extending over the top of the cap, and a cam-lever fulcrumed on the bail and adapted to engage the wearing-plate, 50 substantially as described.

In testimony whereof I affix my signature in presence of two witnesses.

FRANK CANFIELD.
